Specification for Design.

Patented May 6, 1919.

Application filed May 4, 1918. Serial No. 232,651. Term of patent 14 years.

To all whom it may concern:

Be it known that we, HOMER G. KNODERER, a citizen of the United States, residing at Edgeworth, in the county of Allegheny and State of Pennsylvania, and CECIL R. HUBBARD, a subject of the King of Great Britain, residing at Baden, in the county of Beaver and State of Pennsylvania, have invented a new, original, and ornamental Design for a Corner and Twist Box for Electrical-Conductor Conduits, of which the following is a specification, reference being had to the accompanying drawing, forming a part thereof.

Figure 1 is a side elevation of the corner and twist box for electrical conductor conduits, and Fig. 2 is a front elevation of the box as viewed from the right hand side of Fig. 1.

We claim:

The ornamental design for a corner and twist box for electrical conductor conduits as shown.

HOMER G. KNODERER.
CECIL R. HUBBARD.
